Primary Examiner — Dana L Meyrow*(74) Attorney, Agent, or Firm* — Knobbe Martens Olson & Bear LLP(57) **CLAIM**

I claim the ornamental design for a snuff container, as shown and described.

DESCRIPTION

FIG. 1 is a top perspective view of a snuff container according to my new design;

FIG. 2 is a bottom plan view thereof;

FIG. 3 is a front elevation view thereof;

FIG. 4 is a top perspective view of the lid with the lower container portion and the top disposal lid removed;

FIG. 5 is a top plan view thereof; and,

FIG. 6 is a rear elevation view of the snuff container of FIGS. 1-3.
